VALVE.

1,378,141.

Specification of Letters Patent.

Patented May 17, 1921.

Application filed March 15, 1920. Serial No. 365,703.

To all whom it may concern:

Be it known that I, HARVEY SLATER, a citizen of the United States, residing at Chicago, in the county of Cook and State 5 of Illinois, have invented certain new and useful Improvements in Valves, of which the following is a specification.

This invention relates to that general type of high pressure valves covered by my 10 United States Letters Patent No. 1,143,236, and contemplates specifically a double valve composed of units such as disclosed in said patent co-operatively associated for efficient and economical use in connection with a 15 hydraulic press or other type of press operated by a fluid under high pressure.

In the operation of hydraulic presses which have a comparatively long working stroke and which requires a high pressure 20 only near the end of said stroke, at which time the moving die is acting upon the material to be compressed, it has been found advisable to employ both a low and a high pressure fluid. The reason for this is that 25 little compressive work is done until near the bottom of the working stroke, and if only high pressure fluid is employed a great quantity thereof is consumed in simply actuating the piston of the press without 30 accomplishing the high compressive work for which it was intended. This results in inefficiency,—a waste of high pressure fluid, since to build up and maintain such a high pressure requires, as is known, a considerable 35 amount of power.

It has become a practice, therefore, to employ, as stated above, both a high-pressure fluid and a low pressure fluid in the operation of such presses. The low pressure 40 fluid, the pressure in which is comparatively economical to build up, is used for the greater part of the working stroke. The high pressure fluid is then turned into the pressure cylinder of the press by means of 45 some auxiliary valve and the higher compressive work accomplished on the material thereunder.

Two principal objections to this practice have arisen. In the first place it requires 50 the attention of an experienced operator to manipulate, at the proper time, the high-pressure valve. Secondly, inasmuch as the operators employed to run such presses are generally paid on a piece-work basis, or in 55 proportion to the amount of work turned

out, there is a tendency on the part of said operator, in order to hasten each press operation, either to apply the high-pressure fluid too quickly, or, in more flagrant cases, to make use of the high pressure fluid 60 throughout the entire stroke, either of which above mentioned practices would result in inefficient and uneconomical use of pressure.

The present invention, therefore, has for its primary object the provision of co-operating high and low pressure valves which function to automatically introduce a high-pressure fluid to the pressure cylinder only when the piston, actuated by the low pressure fluid, nears the lower part of its working stroke and actually commences its compressive work.

Another object is to provide a valve which is simple in construction, which is fool-proof, and which operates automatically to 75 introduce high pressure fluid at the proper time, thus dispensing with the services of an operator for this particular duty and permitting one operator to attend several presses.

Further objects and advantages of my invention will become evident from the following description and drawings based thereon. Inasmuch as the principle of the invention is capable of being applied in 85 constructional forms other than the one illustrated, it is not intended that the scope of the appended claims should be unnecessarily limited thereby.

In the drawings—

Figure 1 is a top plan view of the double valve;

Fig. 2 is a side elevation of the same;

Fig. 3 is a central, longitudinal section on an enlarged scale;

Fig. 4 is an assembly view showing the pressure cylinder of a press operatively connected with the valve of the present disclosure; and

Fig. 5 is a vertical transverse section on 100 the line 5—5 of Fig. 2.

Having particular reference to the drawings the numeral 11 designates a casing, which contains two parallel and longitudinally disposed bores 12 in which are positioned twin valves, each of which is quite similar to the valve disclosed in my previously mentioned Letters Patent No. 1,143,236. Inasmuch as the twin valves are duplicates a brief description of one will 105 110

suffice for the other, the coefficient "a" being used on the drawings to signify a corresponding part of the other valve.

One end of bore 12 is closed by a screw plug 13. Opening upon said bore and displaced in order longitudinally in the casing 11 are a pressure inlet 14, a machine supply port 15 and an exhaust port 16. The bore 12 of the casing between the inlet 14 and 5 the port 15 contains a sleeve 17 fixedly disposed and held against a shoulder in said bore by the above-mentioned screw plug 13. Packing is positioned between said sleeve and screw plug in order to prevent leakage 10 of the pressure fluid. Sleeve 17 forms in bore 12 an apertured partition which functions as a guide and seat for the inlet controlling valve 18, the stem 19 of which is guided within a bore in the plug 13 and 15 there engaged by a compression spring 20. Said spring acts to maintain the valve 18 in closed position against its seat in sleeve 17. Said sleeve is apertured as at 21, adjacent the pressure inlet 14 in order to permit an inflow of fluid to valve 18. Radial oblique ports 22 are positioned in sleeve 17 below the seat of valve 18 and function to allow the pressure fluid unobstructed passage to the chamber 23 which opens on 20 the machine supply port 15. That portion of valve 18 below its seat in sleeve 17 is contracted for a short portion of its length, below which contraction, it is radially flanged for guiding the valve in said sleeve. 25 The flanged portion of valve 18 extends beyond sleeve 17 into chamber 23, as shown in Fig. 3. A shoulder 24 is formed in bore 12 between the machine supply port 15 and the exhaust port 16. A guide sleeve 25 is 30 fixedly disposed in this portion of the bore and bears upon packing positioned between said sleeve and shoulder. Slidably mounted in the sleeve 25 and adapted to be brought into engagement with the pressure inlet 40 valve 18 is a sliding piston 26 having a passage way 27 extending therethrough which functions to place the machine port 15 in fluid communication with the exhaust port 16. A bonnet 28 is threaded into the end 45 of bore 12 opposite the screw plug 13. The inner end of said bonnet provides a stop for limiting the movement of piston 26 in that direction. The bonnet contains a longitudinal bore, which bore at its inner end 50 is enlarged to form a chamber 29. Said chamber is open to exhaust port 16 which is disposed between the bores 12 and common to each of the twin valves, the communication 55 between said chamber and port being accomplished by apertures 30 in the sidewalls of the bonnet.

Extending through the bore in bonnet 28, and guided thereby is the stem of an exhaust controlling valve 31, the head of 60 which seats in the passage-way 27 of pis-

ton 26 thus closing fluid communication through said passage way. The length of piston 26 is so proportioned that the inlet valve 18, which is opened by the pressing contact of the end of said piston, may move 70 into closed position before the piston is stopped against bonnet 28.

The foregoing description explains the construction of the two valves, positioned in bores 12, which valves, as before stated, are 75 duplicates. The exhaust port 16 therebetween is open to both valves and functions as a common outlet.

A bore 32 is positioned in casing 11 between the bores 12 and has its axis perpendicular to the plane of the axes of bores 12, 12^a, as shown in the drawings. A sleeve 33 is fixedly positioned in bore 32 and contains a small axial bore 34. This partition-like sleeve forms the bore 32 into an upper 80 and a lower chamber, 35 and 36 respectively. Said bore intersects bore 12, thus putting chamber 35 of bore 32 into open communication with chamber 23 of bore 12, as shown in Figs. 3 and 5.

An oblique port 37 through the casing connects chamber 36 with the inlet 14^a.

A pressure valve 38 is guided in a bonnet 39 screwed into the top of bore 32. Said valve seats upon the top of the small bore 95 in sleeve 33 where it is held by the compression of a spring 40 located in said bonnet between the enlarged portion of the valve and a compression adjusting bonnet 41. That part of valve 38 which is exposed 100 in chamber 35 contains a pressure surface or shoulder 42. A screw plug 43 effectively closes the bottom of bore 32.

A cross-head 44 is rigidly disposed at one 105 end of casing 11 by means of the anchoring bolts 45. Said cross-head contains two bores within which are threaded screw spindles 46, 46^a longitudinally aligned with the valve stems 31, and 31^a. Intermeshing gear wheels 47, 47^a, are keyed to the screw spindles. An operating handle 48 is also keyed to spindle 46, so that when, by means of handle 48, one spindle is rotated and moved inward the other will automatically move outward, and vice versa.

A housing 49 covers the gear wheels 47, 47^a and forms a protection for the same.

The operation of this device is as follows:

By means of suitable connecting pipes inlet 14 is connected to a low-pressure fluid supply with an interposed non-return check valve 50, port 15 to that end of a hydraulic press cylinder above the piston head, exhaust port 16 back to the fluid reservoir; inlet 14^a to a high pressure fluid supply and port 15^a to that end of the hydraulic press cylinder below the piston head, substantially as illustrated in Fig. 4. Inasmuch as the stem of the piston in the above mentioned cylinder occupies the greater part of the 110 115 120 125 130

cylinder space below the head of the piston, and only a small area of the piston shoulder is exposed in the cylinder to the liquid, it is desirable to use high pressure fluid on the 5 return stroke, since a comparatively high pressure is needed, and only a small quantity thereof is consumed in this operation.

Assume for the purposes of exemplification that the pressure at the low pressure inlet 14 is 200 pounds, and at the high pressure inlet 14^a, 1,000 pounds. As shown in Fig. 3 the valves in this device are closed. In order to operate the press, the screw spindle is moved inwardly by rotation of handle 15 48 in a clock-wise direction. Said spindle impinges against the stem of valve 31, said valve, which is seated against the piston 26, actuates the piston and said piston unseats valve 18, permitting the low pressure fluid to 20 flow into chamber 23 and through the port 15 into that part of the hydraulic press cylinder above the piston.

At the same time the screw spindle 46^a being actuated, because of the gear wheels 25 47, 47^a in a direction opposite to that of spindle 46 allows the valve 31^a to unseat from piston 26^a and permits the fluid below the piston in the hydraulic cylinder to pass from port 15^a into the exhaust port 16, the 30 valve 18^a meanwhile remaining closed.

Since port 37 is always in open communication with the high pressure inlet 14^a valve 38 (Fig. 5) is adjusted by means of the bonnet 41 acting on spring 40 to prevent 35 the unseating of said valve by the high pressure fluid acting on the small area of the lower reduced end thereof from chamber 36. However, when the pressure in chamber 35, which is equivalent to that pressure above 40 the piston in the hydraulic cylinder, rises to near its maximum (in this case 200 pounds) due to the retarding of the piston upon coming in contact with the material to be compressed, this added pressure of approximately 200 pounds acting on the larger area of the shoulder 42 of valve 38 is sufficient when coöperating with the high pressure below said valve to compress spring 40 and raise the valve from its seat.

50 As said valve thus opens fluid communication between the high pressure fluid inlet 14^a and the machine supply port 15, the high pressure fluid is introduced into the cylinder and acts upon the piston, at high 55 pressure in lieu of the previous low pressure. Thus the high pressure fluid is applied to the piston during that portion only of its stroke when high pressure is required to perform the work. The previously mentioned check valve 50, disposed in the connecting pipe leading to the low pressure supply port 14, prevents a back flow therethrough.

When it is desired that the pressure behind 60 the piston be released and the piston be re-

turned to its initial position, the handle 48 is rotated in a contra clock-wise direction, thus causing spindle 46 to move outward and spindle 46^a to move inward. Valve 18, being no longer held open against the compression of spring 20, is seated and closes communication with the inlet supply port 14. Valve 31 is unseated from piston 26 due to the pressure built up in chamber 23 and passage 27, thus permitting the discharge of 70 fluid from the machine supply port to the exhaust port 16. As soon as the pressure in the machine supply port 15 has dropped sufficiently, the pressure actuated valve 38 in bore 32 automatically closes.

At the same time, due to the movement of spindle 46^a, valve 31^a, and piston 26^a, valve 18^a is unseated and valve 31^a seated and securely held against its seat in piston 26, permitting high pressure fluid from inlet 14^a to 85 flow past valve 18^a into machine supply port 15^a and closing off fluid communication between said machine support port and exhaust port 16. In this manner the piston of the 90 hydraulic press is actuated by the high pressure fluid on its return stroke, thus completing a cycle of the press.

It will thus be seen that by the employment of my improved valve in connection with sources of supply of high and low 95 pressure fluid, I am enabled to most economically utilize low pressure fluid during the greater portion of the working stroke of a press, drawing upon the high pressure supply only as and when high compressive 100 work is required of the press, and quickly returning the press platen at the end of its work stroke by the comparatively small expenditure of high pressure fluid; all with automatic certainty and precision.

I claim:

1. In a device of the character described, the combination of two valve mechanisms each including an inlet, an exhaust and a machine-supply port, means in each of said mechanisms whereby its machine-supply port is put in alternate communication first with its inlet and then with its exhaust, means for operating both valve mechanisms in synchronism whereby when communication between the machine-supply port and inlet of one is opened communication between the machine-supply port and exhaust of the other is opened, and vice versa, and means to establish communication between the inlet of one 110 valve mechanism and the machine-supply port of the other whereby when the pressure in the latter port reaches a predetermined amount communication will automatically open therebetween.

2. In a device of the character described, the combination of two valve mechanisms each including an inlet, an exhaust and a machine-supply port, the inlets connected respectively one to a source of low pressure 115 120 125 130

- fluid and the other to a source of high pressure fluid, means in each of said mechanisms whereby its machine-supply port is put in alternate communication first with 5 its inlet and then with its exhaust, means for operating both valve mechanisms in synchronism whereby when communication between the machine-supply port and inlet of one is opened communication between the 10 machine-supply port and exhaust of the other is opened, and vice versa, and means to establish communication between the high pressure inlet of one valve mechanism and the machine-supply port of the other whereby 15 by when the pressure in the latter port reaches a predetermined amount communication will automatically open therebetween.
3. In a device of the character described, the combination of two valve mechanisms 20 each including an inlet, an exhaust and a machine-supply port, the inlets connected respectively one to a source of low pressure fluid and the other to a source of high pressure fluid, a non-return check valve positioned in the connection leading to the low pressure fluid inlet, means in each of said mechanisms whereby its machine-supply port is put in alternate communication first with its inlet and then with its exhaust, 25 means for operating both valve mechanisms in synchronism whereby when communication between the machine-supply port and inlet of one is opened communication between the machine-supply port and exhaust 30 of the other is opened, and vice versa, means to establish communication between the high pressure inlet of one valve mechanism and the machine-supply port of the other whereby when the pressure in the latter port reaches 35 a predetermined amount communication will automatically open therebetween.
4. In a device of the character described, the combination of two valve mechanisms each including an inlet, an exhaust and a 40 machine-supply port, means in each of said mechanisms whereby its machine-supply port is put in alternate communication first with its inlet and then with its exhaust, said means comprising in each mechanism a normally closed inlet valve disposed between the inlet and the machine-supply port and an exhaust valve between the machine-supply port and exhaust, the valves being co-operatively positioned whereby the inlet 45 valve is caused to open or close by the respective closing or opening of the exhaust valve, means for operating both valve mechanisms in synchronism whereby when communication between the machine-supply port and inlet of one is opened communication between the machine-supply port and exhaust of the other is opened, and vice versa, and means to establish communication between the inlet of one valve mechanism and 50 the machine-supply port of the other where- 55

by when the pressure in the latter port reaches a predetermined amount communication will automatically open therebetween.

5. In a device of the character described, the combination of two valve mechanisms 70 each including an inlet, an exhaust and a machine-supply port, means in each of said mechanisms whereby its machine-supply port is put in alternate communication first with its inlet and then with its exhaust, 75 means for operating both valve mechanisms in synchronism whereby when communication between the machine-supply port and inlet of one is opened communication between the machine-supply port and exhaust 80 of the other is opened, and vice versa, said means comprising two screw spindles alined in operative contact with the stems of said exhaust valves, intermeshing gears keyed on said spindles, means provided on one of 85 said spindles for rotating the same, and means to establish communication between the inlet of one valve mechanism and the machine-supply port of the other whereby when the pressure in the latter port reaches 90 a predetermined amount communication will automatically open therebetween.

6. In a device of the character described, the combination of two valve mechanisms each including an inlet, an exhaust and a 95 machine-supply port, means in each of said mechanisms whereby its machine-supply port is put in alternate communication first with its inlet and then with its exhaust, means for operating both valve mechanisms 100 in synchronism whereby when communication between the machine-supply port and inlet of one is opened communication between the machine-supply port and exhaust of the other is opened, and vice versa, and 105 means to establish communication between the inlet of one valve mechanism and the machine-supply port of the other whereby when the pressure in the latter port reaches 110 a predetermined amount communication will automatically open therebetween, said last mentioned means comprising a passage therebetween, a pressure actuated valve disposed in the passage, said valve presenting an effective pressure surface to the inlet and another effective surface to the port, and a compression spring normally holding said valve closed against its seat.

7. In a device of the character described, the combination of two valve mechanisms 115 each including an inlet, an exhaust and a machine-supply port, means in each of said mechanisms whereby its machine-supply port is put in alternate communication first with its inlet and then with its exhaust, 120 means for operating both valve mechanisms in synchronism whereby when communication between the machine-supply port and inlet of one is opened communication between the machine-supply port and exhaust 125 of the other is opened, and vice versa, and means to establish communication between the machine-supply port and exhaust 130

- of the other is opened, and vice versa, and means to establish communication between the inlet of one valve mechanism and the machine-supply port of the other whereby 5 when the pressure in the latter port reaches a predetermined amount communication will automatically open therebetween, said last mentioned means comprising a passage therebetween, an inwardly opening pressure 10 sure-actuated valve disposed in the passage, said valve presenting an effective pressure surface to the inlet and another effective pressure surface to the port, and a compression spring normally holding said valve closed 15 against its seat, and means for adjusting said spring to determine the combined pressure acting on the valve at which the valve will open.
8. In a device of the character described, 20 the combination of two valve mechanisms each including an inlet, an exhaust and a machine-supply port, the inlets connected respectively one to a source of low pressure fluid and the other to a source of high pressure 25 fluid, a non-return check valve positioned in the connection leading to the low pressure fluid inlet, means in each of said mechanisms whereby its machine-supply port is put in alternate communication first 30 with its inlet and then with its exhaust, said means comprising in each mechanism a normally closed inlet valve disposed between the inlet and the machine-supply port and an exhaust valve between the machine-supply 35 port and exhaust, the valves being cooperatively positioned whereby the inlet valve is caused to open or close by the re- spective closing or opening of the exhaust valve, means for operating both valve mechanisms in synchronism whereby when communication between the machine-supply port and inlet of one is opened communication between the machine-supply port and exhaust of the other is opened, and vice versa, said means comprising two screw 40 spindles alined in operative contact with the stems of said exhaust valves, intermeshing gears keyed on said spindles, means provided on one of said spindles for rotating the same, and means to establish communication between the high pressure inlet of one valve mechanism and the machine-supply port of the other whereby when the pressure in the latter port reaches a predetermined amount communication will automatically 45 open therebetween, said last mentioned means comprising a passage therebetween, an inwardly opening pressure-actuated valve disposed in the passage, said valve presenting an effective pressure surface to 50 the inlet and another effective pressure surface to the port, and a compression spring normally holding said valve closed against its seat, and means for adjusting said spring to determine the combined pressure acting 55 on the valve at which the valve will open.
- In testimony whereof I have hereunto signed my name in the presence of two subscribing witnesses.
